UNITED STATES PATENT OFFICE.

PAUL GIFFARD, OF PARIS, FRANCE.

IMPROVEMENT IN COMPRESSED-AIR DEFENSE-STICKS.

Specification forming part of Letters Patent No. 136,316, dated February 25, 1873.

To all whom it may concern:

Be it known that I, PAUL GIFFARD, of Paris, in the Republic of France, have invented a new and Improved Air Defense-Stick; and I do hereby declare the following, when taken in connection with the accompanying drawing and the letters of reference marked thereon, to be a full, clear, and exact description of the same, and which said drawing constitutes part of this specification, and represents a longitudinal central section.

This invention relates to an improvement in what is termed an air defense-stick—that is to say, a cane provided with a barrel and means for discharging the ball or shot therefrom; and the invention consists in an air-chamber inclosing a pump for compressing air into the said chamber, combined with a barrel and a valve for opening communication between the air-chamber and the said barrel, the said valve operated by a bolt and lever, as more fully hereinafter described.

The cane is formed in two parts, the upper part A being a cylinder or air-reservoir, and the lower part S the barrel. Within the air-chamber A is the pump-cylinder B, within which the piston C is operated by the rod D through the head E, the said piston forcing air through the valve F into the space between the cylinder A and pump-cylinder B until the requisite pressure is attained. A suitable packing, E', is introduced at the head to prevent the escape of air. Between the barrel and

air-chamber a small opening, n, is made, closed by a valve, I, opening from the air-chamber. A spindle, m, is attached to the valve, and works freely longitudinally in a perforated guide, G. The lower or barrel portion separates from the upper portion immediately below the guide G. Below the valve a bolt, L, is arranged, sliding transversely and bearing upon the valve so as to hold it firmly in its seat, and in connection therewith is a lever, L', which may be turned up to the position denoted in broken lines, and when in that position a slight additional movement will draw the bolt L and allow the air to escape and pass instantly to the barrel, there operating upon the ball or charge in similar manner as in air-guns.

I claim as my invention—

The herein-described defense-stick, consisting of the air-chamber A, with the air-pump B arranged therein to charge the said chamber, the barrel S with the opening n between the air-chamber and barrel provided with the valve I, and combined with the bolt L and lever L', the whole constructed and arranged to operate substantially as set forth.

In testimony whereof I have signed my name to this specification before two subscribing witnesses.

PAUL GIFFARD.
